DE 2725846 A 12/1978

Primary Examiner — Deanna L Pratt

(74) Attorney, Agent, or Firm — Adam R. Stephenson, Ltd.

(57) **CLAIM**

The ornamental design for ergonomic scissors, as shown and described.

DESCRIPTION

FIG. 1 is a top perspective view of an implementation of ergonomic scissors;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The broken lines illustrate portions of the ergonomic scissors that form no part of the claimed design.

1 Claim, 5 Drawing Sheets
